AIR CONDITIONER CABINET OR SIMILAR ARTICLE

Robert D. Budlong, Skokie, Ill., assignor to Amana Refrigeration, Inc., Amana, Iowa, a corporation of Iowa

Application February 3, 1954, Serial No. 28,816

Term of patent 14 years

(Cl. D62—4)

To all whom it may concern:

Be it known that I, Robert D. Budlong, a citizen of the United States, residing at Skokie, in the county of Cook and State of Illinois, have invented a new, original, and ornamental Design for an Air Conditioner Cabinet or Similar Article, of which the following is a specification, reference being had to the accompanying drawing, forming a part thereof.

In the drawings:

Figure 1 is a perspective view of an air conditioner cabinet or similar article showing my new design;

Figure 2 is a side elevational view thereof;

Figure 3 is a front elevational view. The dominant features of my design reside in the portions shown in full lines.

The side opposite the side shown in Figure 2 is the same as the side shown in Figure 2.

I claim:

The ornamental design for an air conditioner cabinet or similar article, substantially as shown and described.
